UNITED STATES PATENT OFFICE.

ROBERT E. EINSTEIN, OF ST. LOUIS, MISSOURI, ASSIGNEE TO ST. LOUIS FROG AND SWITCH COMPANY, OF ST. LOUIS, MISSOURI, A CORPORATION OF MISSOURI.

MANGANESE-TIP SWITCH.

1,186,560.

Specification of Letters Patent. Patented June 13, 1916.

Application filed February 9, 1910. Serial No. 77,239.

To all whom it may concern:

Be it known that I, ROBERT E. EINSTEIN, a citizen of the United States, residing at St. Louis, Missouri, have invented a certain new and useful Improvement in Manganese-Tip Switches, of which the following is a full, clear, and exact description, such as will enable others skilled in the art to which it appertains to make and use the same.

This invention relates to split switches of the type in which the switch points are provided with hard tips or end portions formed of manganese steel, or some other suitable hard metal that has great wear-resisting properties.

The weak point in a manganese tip split switch is the connection between the tips and the switch points or switch rails that carry same.

One object of my invention is to provide a hard tip split switch which is so constructed that there is no liability of the switch rails breaking at the joints between the wheel tread surfaces of the rails and the hard tips that are connected to the rails.

Another object is to provide a switch of the type mentioned, in which the tips are connected to the switch points or switch rails in such a manner that there is no liability of their working loose when the switch is in service. To this end I have devised a hard tip split switch in which the tip on each switch rail is provided with an integral reinforcing device arranged at the joint between the wheel tread surfaces of the tip and the switch rail, so as to reinforce and strengthen the switch rail at the point where it is most liable to break, when the switch is in service, said reinforcing device prefer-

ably being in the form of a clip or bracket that serves to connect the usual switch rod to the switch rail. The web of the switch rail preferably extends throughout the entire length of the tip and the tip is provided with integral portions that embrace both sides of the web of the rail, so as to reduce the strain on the fastening devices used to secure the tip to the rail, thereby effectively preventing the tip from working loose from the switch rail.

Figure 1 is a top plan view of a split switch constructed in accordance with my invention. Fig. 2 is a longitudinal sectional view of said switch, taken on the line 2-2

of Fig. 1. Figs. 3, 4 and 5 are cross-sectional views, taken on the lines 3-3, 4-4 and 5-5, respectively, of Fig. 2; and Fig. 6 is a perspective view of one of the hard tips that the switch points or switch rails 60 are provided with.

Referring to the drawings, which illustrate the preferred form of my invention, A designates the switch points or switch rails of a split switch, B designates the stock 65 rails with which the switch points cooperate, and C designates switch rods of any suitable type that join the switch points together and cause them to move in unison. Each of the switch rails A is provided with 70 a tip D formed of manganese steel, or some other suitable hard material that forms the thin end portion of the switch point. The tip D is provided with a wheel tread surface 1 that forms a continuation of the wheel 75 tread surface 1^a of the switch rail to which it is connected, and said tip is connected to the web 2 of the switch rail by means of rivets or other suitable fastening devices 3 that pass horizontally through the web of 80 the switch rail and through the vertical web 4 of the tip. In the preferred form of my invention as herein shown the web 2 of the switch rail extends throughout the entire length of the tip D to the end of said tip, 85 as shown in broken lines in Fig. 2, and the web 4 of the tip extends rearwardly beyond the joint between the wheel tread surfaces of the tip and the switch rail so that it will lap over the web of the switch rail 90 some distance beyond the joint x.

In order to reinforce and strengthen the structure at the joint x where it is most liable to break when the switch is in service, I have provided the tip D with an integral 95 reinforcing device that is arranged at the joint x, said reinforcing device preferably being in the form of a laterally-projecting bracket or clip E that serves to connect one of the switch rods C to the switch rail A. 100 The clip E is provided with a horizontally-disposed base portion 5 that projects laterally from the lower edge of the web 4 of the tip D, so that it will bear upon the base flange of the switch rail, as shown in 105 Fig. 5, and at the outer end of said base portion 5 is an integral yoke or horizontally-disposed U-shaped portion 6 that receives the switch rod C, said switch rod being connected to said yoke by a bolt or other suit- 110

able fastening device 7 that passes vertically through said parts. The case portion of the clip E is reinforced and strengthened by one or more vertically-disposed ribs 5^a that are integrally connected to same and to the vertical web 4 of the tip D, the clip E herein shown having two reinforcing ribs 5^a whose upper edges taper downwardly and merge into the yoke-shaped portion 6 at the outer end of the clip. An integral switch rod clip E' of similar form is arranged adjacent the other end of the tip D, so as to coöperate with the other switch rod C, as shown in Fig. 1.

In order to eliminate the possibility of the tip D working loose from the switch rail, I have formed the tip D in such a manner that integral portions on same bear against both sides of the web of the switch rail over which the wheel tread portion 1 of the tip extends. It is immaterial how the tip D is formed to accomplish this result, as my broad idea consists in providing the tip with one or more integral portions that coöperate with the portion of the switch rail on which the tip is mounted, to prevent the tip from moving laterally away from the switch rail. In the embodiment of my invention herein illustrated the upper portion of the tip D is provided with a longitudinally-disposed groove 8 that receives the upper edge portion of the web 2 of the switch rail, thus forming a flange 9 on the tip that extends parallel to the web 4 of the tip. Said flange 9 may be of any preferred depth and length, or, if desired, the tip D may be provided with one or more short lugs or hook-shaped portions that merely lap over the upper edge of the web 2 of the switch rail. The upper edge of that portion of the web 2 of the switch rail that fits in the groove 8 in the tip is preferably tapered or made substantially wedge-shaped in cross section and the groove 8 is correspondingly shaped, as shown in Fig. 5, so as to overcome the necessity of machining the tip during the operation of combining it with the switch rail. If desired, a splice bar 10 can be arranged on the inner side of the web of the switch rail in parallel relation to the web 4 of the tip, as shown in Figs. 3, 4 and 5, so as to strengthen the connection between the tip D and the switch rail.

A manganese tip split switch of the construction above described is exceptionally strong and rigid, owing to the fact that the tip is provided with an integral reinforcing device arranged at the joint between the wheel tread surface of the tip and the switch rail, so as to reinforce and strengthen the switch rail at the point where it is most liable to break when the switch is in service. This reinforcing device is in the form of a switch rod clip, and therefore it performs

two functions,—namely, it reinforces and strengthens the complete structure, and it constitutes an integral switch rod clip that is not apt to work loose. The web of the switch rail extends throughout the entire length of the tip, and as the tip is provided with integral portions that bear upon both sides of said web, there is little liability of the tip working loose when the switch is in service. In addition to the desirable features above mentioned, a manganese tip split switch of the construction above described can be manufactured cheaply, owing to the elimination of separate switch rod clips and to the novel manner in which the tip is combined with the switch rail. Furthermore, as the switch rod clip is made of manganese steel or some other suitable metal that is harder than the metal heretofore used for switch rod clips, the hole in the clip through which the switch rod bolt passes will not wear or become enlarged, thus overcoming the necessity of frequently replacing the switch rod clip, and consequently, reducing the cost of maintenance.

Having thus described my invention, what I claim, and desire to secure by Letters Patent, is:

1. In a split switch, a switch point or rail equipped with a hard metal tip provided with an integral device that reinforces and strengthens the structure at the joint between the wheel tread surfaces of the tip and the rail.
2. A switch point or rail provided with a hard metal tip that constitutes the end portion of the switch point, said tip having an integral, laterally-projecting reinforcing device that is arranged at the joint between the wheel tread surfaces of the tip and the rail.
3. A switch point or rail consisting of a member provided with a vertical web and a wheel tread portion, a hard metal tip connected to said web and provided with a wheel tread portion that forms a continuation of the wheel tread portion on said member, and an integral switch rod clip on said tip arranged adjacent the joint between the wheel tread portions of said tip and said member.
4. A switch point or rail for split switches equipped with a hard metal tip that is provided with an integral switch rod clip.
5. A split switch provided with a switch point or rail whose end portion is formed by a hard metal tip that is provided with an integral, laterally-projecting device that is arranged in proximity to the joint between the coöoperating wheel tread surfaces on the tip and on the switch rail.
6. In a split switch, a switch point or rail, a hard metal tip connected to said rail so as to form the end portion of the switch point, and integral devices on said tip to

which switch rods are adapted to be connected.

7. In a split switch, a switch point or rail, a hard metal tip connected to said rail so as to form the end portion of the switch point, and integral devices on said tip to which switch rods are adapted to be connected, one of said devices being arranged at the joint between the wheel tread surfaces of the tip and the switch rail.

8. In a split switch, a switch point or rail provided with a hard metal tip that constitutes the thin end portion of the switch point, and a laterally-projecting bracket integrally connected to said tip and provided with a yoke-shaped portion for receiving a switch rod.

9. In a split switch, a switch point or rail consisting of a member provided with a wheel tread portion and with a vertical web that projects forwardly beyond said wheel tread portion, a hard metal tip connected to said web and provided with a wheel tread portion that forms a continuation of the wheel tread portion on said member, and an integral reinforcing device on said tip arranged at the joint between the wheel tread portions of said tip and member.

10. A switch rail for split switches provided with a hard metal tip that constitutes the thin end portion of the rail, the web of the rail extending throughout the entire length of the tip and said tip being provided with an integral, laterally-projecting switch rod clip that is arranged at the joint between the wheel tread portion of the tip and the wheel tread portion of the rail.

11. A switch point or rail for split switches provided with a hard metal tip that constitutes the thin end portion of the switch rail, the web of the switch rail extending throughout the entire length of said tip and said tip having a web portion that laps over the web of the rail some distance at the rear of the joint between the coöperating wheel tread portions of the tip and the rail, and an integral switch rod clip on said tip arranged at said joint.

12. A switch point or rail for split switches provided with a hard metal tip that constitutes the thin end portion of the switch point, a vertical web on said tip that

is connected by suitable fastening devices to the web of the rail, and a longitudinally-extending groove in said tip of substantially inverted V shape in cross section that receives a tapered portion on the web of the rail.

13. A switch point or rail for split switches provided with a hard metal tip that comprises a web portion which is connected by means of fastening devices to the web portion of the rail, integral means on said tip that tends to prevent it from moving laterally away from the web of the rail and thus reduces the strain on said fastening devices, and an integral switch rod clip on said tip arranged at the joint between the wheel tread surfaces of said tip and said rail.

14. A tip for switch points, consisting of a member formed from hard metal and comprising a vertical web provided with an integral portion for lapsing over the upper edge of the switch point to which the tip is connected, and an integral switch rod clip projecting laterally from the vertical web of said member.

15. A hard metal tip for switch points provided with a vertically-disposed web, an integral bracket projecting laterally from said web and provided at its outer end with a yoke-shaped portion to which a switch rod can be connected, and a vertically-disposed flange on said bracket that is integrally connected to said web.

16. A hard metal tip for switch points provided with a vertically-disposed web, an integral bracket projecting laterally from said web and provided at its outer end with a yoke-shaped portion to which a switch rod can be connected, a vertically-disposed flange on said bracket that is integrally connected to said web, and an integral portion on said web that is adapted to lap over the upper edge of the switch point to which the tip is connected.

In testimony whereof I hereunto affix my signature in the presence of two witnesses, this third day of February, 1916.

ROBERT E. EINSTEIN.
